FASTENING-SUPPLYING APPARATUS

John T. Lancaster, Newton, Mass., assignor to
 United Shoe Machinery Corporation, Borough
 of Flemington, N. J., a corporation of New
 Jersey

Application May 2, 1938, Serial No. 205,497

107 Claims.

(Cl. 1—39)

My invention relates to apparatus by which fastenings are supplied in loads of one or more in number to a machine by which such fastenings are to be inserted, it being especially directed to the delivery of nails or the like in successive groups, from a mass contained in a receptacle forming a part of a distributor and advanced therefrom by the loading means of this apparatus to the receiving machine.

Because of irregularities in the form of nails, it is difficult to insure their delivery by automatic means in full groups or loads. When a load with a missing nail or nails is fed into a loading device for transfer to a machine for attaching heels to shoes, it is necessary that incomplete loads be noted, and the defect corrected. If this is not possible, the work produced is faulty. If each load can be inspected, and the missing nails supplied, it produces a substantial loss of time. It is an object of my invention to guard against the delivery of a partial load. In the attainment of this object, I test each load or group of fastenings to determine its completeness by means acting between means which separates the loads from the mass and means which delivers said loads to the machine to be supplied. Unless there is a full load, its delivery is impossible, and the operator needs only to provide the fastenings which the apparatus itself has determined to be missed. Under no conditions can a partial load be fed. Preferably, a distributing or loading member, as an oscillatory roll provided with a fastening-receiving passage supplied from a race-way, temporarily holds the fastenings during their delivery to the machine to be supplied. A co-operating testing means or feeler, affected by the absence of a fastening or fastenings at the holder, controls their delivery and the operation of the machine to be supplied, thus preventing their use. The roll or other holder is preferably movable in a casing having delivering, receiving and testing openings for the fastenings, into registration with which openings the holder-passage may be moved. In this movement, the holder may invert the fastening contained in the passage. To determine the position of the holder-roll, a device, as a rotatable cam, is provided for controlling rotation to certain of its positions, as those for receiving and testing, there being associated with this device other means for turning the roll to its delivering position. A member movable by the operator controls the rotation of the roll through the oscillation of a primary lever, and the other means by which the roll is turned is governed by a member movable through a secondary lever in the control of the machine supplied with fastenings. In the operation of the secondary lever, movement is also imparted to a member which governs the movement of the primary lever, which releases for the shifting of the fastening-roll from the testing to the delivering position. In the illustrative form of the invention, the controlling means for the testing member consists of two disks, one rotatable with or as a part of the holder-roll and the other rotatable relatively thereto. In the periphery of each disk is a depression, and when these depressions are in registration, a lever or like member acting upon the feeler or feelers may enter said depressions to produce the testing effect. There is means, as a cam-incline upon the periphery of one of the disks, for removing the lever from the depressions. This withdraws the feeler from the roll-passage and prepares for the rotation of the roll after the testing has been performed. When the feeler fails to find a nail in the passage, it actuates a stop member, which both prevents operation of the machine which the apparatus supplies and the movement of the disks or other controlling means which would permit fastening-delivery from the roll. The inserting operation therefore cannot proceed until a full load of nails is ready for delivery. To facilitate the introduction into the holding-passage of a missing fastening, a loading member movable by the operator is provided. The holding-passage preferably extends through the roll, and the automatically operated testing means is movable into one end thereof, while at the opposite end, the manually operated loading means may introduce fastenings into the passage. I have shown this manual loading means as in the form of a rod, guided to reciprocate in an opening in the casing in which the holder-roll is rotatable. A slot admits a nail to the opening, whereupon movement of the rod carries the nail into the roll-passage and forces out the feeler, which found such passage empty. In its inward position, which is the normal or operating relation, the loader-rod is latched. Means movable with the rod closes the fastening-receiving slot against the entrance of dirt in this normal position. To guard against the delivery of a double load of fastenings by the apparatus, the operator-actuated member, which controls the movement of the holding and delivering member and of a transferring device, has means for locking it against movement by the operator, this lock being released as a result of the movement of a second operator-governed member, as one movable in the control of the machine supplied by the apparatus. As particularly disclosed herein, a rotatable cam operates the nail-roll through a lever which initially is out of engagement with the cam and which is governed by a hand-lever. A lock retains the hand-lever against movement under the control of the cam-lever in its initial relation, and this lock is removed when the cam-lever is released for engagement with the cam. The release is effected in the control of the machine supplied, so the de-

livery of a load of nails may be produced only after the machine has utilized the preceding load.

Another object of the invention is to maintain 5 from a mass of nails or other fastenings in the distributing portion of the apparatus, a regular supply, by simple and effective means, and in such a manner that a plurality of sizes may be fed simultaneously. For this purpose, there is 10 rotatable in a stationary receptacle disks fixed to a shaft and provided with elevating buckets delivering to raceways, these buckets being shown as staggered upon opposite sides of the disks. The disks divide the receptacle into separate compartments, 15 in each of which fastenings differing in size or form from those in other compartments may be held. A cover is shown as hinged upon the receptacle, having a portion extending over each of the one or more raceways to protect 20 these. To free the raceway or raceways from crossed fastenings, rotatable clearing means is carried by the cover, gearing which turns the shaft and disks also rotating the clearing means.

A further object of the invention is to pick 25 off accurately, one by one, for delivery from each raceway, successive fastenings. For this purpose, I employ a member movable at the end of a raceway and having a flexible projection arranged to engage the terminal fastening and separate 30 it from the raceway. This projection is preferably in the form of a spring-wall, which is at the outer side of a recess in the wall of an oscillatory cylinder contained in a casing at the end of the raceway. The fastening-engaging end of the projection 35 is inclined downwardly and rearwardly with respect to the direction of separating movement. Such a separator will yield without clogging or breaking, if it does not engage the fastenings in the best relation, and will gradually 40 straighten fastenings which have become inclined from the vertical. In its separation, a fastening enters a space between the end of the outer or flexible wall and the wall furnished by the recess in the cylinder and is drawn off from the raceway 45 by the outer wall. The fastening is then carried by the end of the recess to a delivery-opening in the casing, such opening being larger than the head of the nail. Each of the separating cylinders for plural raceways is rotated by a yieldable connection 50 between it and its actuating means. In the present instance, there is a toothed member, as a rack-block, meshing with the teeth upon each cylinder, there being a reciprocating actuating member common to the toothed members. 55 The movement of the common actuating member is transmitted to the various toothed members or blocks through springs, so breakage is avoided if clogging occurs. I have illustrated herein a cover for each of the casings enclosing the separating cylinders, this cover being hinged upon the projection from the receptacle-cover, which extends over the raceway.

In the accompanying drawings, which illustrate one of the many possible embodiments of 65 this invention:

Fig. 1 shows my improved apparatus in side elevation in place upon the column of a heel-attaching machine;

Fig. 2 is an elevation, viewing the apparatus 70 from the front;

Fig. 3, a top plan view;

Fig. 4, an enlarged top plan view of one of the nail-separating cylinders and the adjacent portion 75 of the raceway;

Fig. 5, a vertical longitudinal section through the same elements as appear in Fig. 4;

Fig. 6, an enlarged, vertical, sectional detail through the nail-delivering mechanism, with the nail-roll in testing position;

Fig. 7, a similar view, with the elements in 5 delivering position;

Fig. 8, a like view of the nail-roll and more closely associated elements, illustrating the manner of introducing a missing nail into the roll; 10

Fig. 9, a sectional detail on the line IX—IX of Fig. 8, and

Fig. 10, a detail in perspective of the actuating means for the nail-roll.

The body or frame of the apparatus may be in 15 the form of an integral casting having a base-portion 10, by which it is mounted upon the top of the frame of the heelng machine F, the jack of which is to be supplied with nails in successive loads. Above the base is a semicylindrical trough 20 (Fig. 1), which provides the lower half of a nail-drum or receptacle of a distributor. At the forward side of the trough are downwardly inclined extensions 14 spaced from one another, upon which raceway-bars 16 are secured. From 25 the forward extremity of each portion 14, shown therewith as a part of the base-casting, extend short, horizontal arms 18. In each of the arms is a vertical bore furnishing a casing 20 to receive a separating cylinder and horizontal bores 22 in 30 depending portions 23 of the arms, the latter bores having rotating within them a nail-roll common to all. The cylinders and roll will later be described in detail.

Pivoted at 24 upon the trough 12 is a cover-portion 26 for the nail-receptacle, this being extended forwardly at 28 to furnish covers for the projecting ends of the raceways. A spring-plunger 27, yieldable upon the cover and entering either of two depressions in a lug 29 projecting from the trough-portion, retains said cover in either its open or closed position. Rotatable in standards 30, 30 at the ends of the nail-receptacle is a shaft 32 having secured to it pairs of circular plates 34, 34 situated at opposite sides of the inner ends of the raceways, the peripheries of these plates moving in close proximity to the interior of the trough and cover. The outer plates of the entire series furnish closures for the ends of the receptacle. At the opposite faces of the plates, within the receptacle, are secured buckets 36, inclined in the usual manner to lift the nails from masses contained in the compartments between the plates and drop them on upwardly diverging retaining walls 38, secured to the opposite sides of the raceway-bars 16. The sets of buckets on the plates may be staggered with respect to each other, to reduce the weight of the nails lifted simultaneously and therefore the load upon the driving mechanism. 50 Each compartment between the plates 34 may contain nails differing in character from those in the companion compartments, or the division of the receptacle may be utilized to reduce the mass which would be held together in a continuous receptacle. When the nails are to be changed, they may be removed through doors 39 pivoted at the bottom of the trough 12 and individual to the respective compartments. The driving of the plates and buckets may be effected 55 by a gear 40 fast upon a horizontal shaft 42, which is driven from a main vertical shaft 46 and a vertical countershaft 45, through spur-gearing 47 and worm-gearing 49. The gear 40 meshes with a large gear 48 secured to the shaft 60 55

32, the movement being in the direction of the arrow in Fig. 1. The gear 48 also meshes with a pinion 50, upon a shaft 52 journaled upon the cover 26 and having a second pinion 55 meshing 5 with a pinion 54 upon a shaft 56 also rotatable upon the cover. On the shaft 56, which extends the full width of the cover, is a series of toothed clearing disks 58, one of which is furnished by the pinion 54. These disks turn in close proximity to the upper surfaces of the raceways and act to sweep back into the receptacle crossed nails which tend to interfere with the advance of the nails properly hanging by their heads upon the bars 16.

15 Referring particularly to Figs. 3, 4, 5 and 10, I have arranged to turn in the casings 20, cylinders 60, one for each raceway-slot. The cylinders are protected, with capacity for ready access to them, by individual covers 62 pivoted at 64 on the cover-20 portions 28 and having finger-pieces 66 by which they may be thrown back. On the periphery of each cylinder are gear-teeth 68, with which meshes a rack-block 70 guided in depressions in the ends of the arms 18. Through the entire 25 series of blocks passes a spindle 72, in which are recesses, each containing a compression-spring 74. One extremity of this spring abuts against the end-wall of its recess, while the other contacts with a projection 76 from the corresponding 30 rack-block 70. Thus, when the spindle is moved to the right, as viewed in Fig. 3, the rack-blocks yieldably turn the cylinders 60 in their casings. As best shown in Fig. 4, each cylinder 60 has a slot 80 formed between a vertical wall 81 of a 35 recess in the side of the cylinder, this wall being curved inwardly and rearwardly, as said cylinder is rotated for delivery, and an outer wall provided by a spring separating finger 82 secured to the cylinder at 84. Normally, an opening at 86, 40 between the end of the spring-wall 82 and the cylinder-wall 81, is alined with its raceway-slot. As the nails descend each raceway-slot in a series, that leading is received by this space 86, and as the cylinder turns, the forward edge 90 (Fig. 5) 45 of the spring-wall separates the nail from those succeeding it in the raceway. As the rotation continues, it brings an enlarged end 92 of the slot 80 against the nail and transfers it to an opening 94 through the bottom of the casing 20. 50 The diameter of both the vertical openings 92 and 94 is such as to pass the head of the nail. The yieldability of the wall 82 guards against breakage if the edge 90 does not strike accurately between nails, the wall being deflected somewhat as pressure is applied by it. That outward deflection may not be interfered with, the ends of the raceway-bars are relieved or concaved at 93. The edge 90 of the wall 82 is curved downwardly and rearwardly. If the shank of the hanging 55 nail happens to be displaced inwardly from the vertical, this edge will have a gradual straightening effect, drawing the entire nail into the slot 80 as it removes it from the raceway. To guard against the terminal nail being jarred rearwardly 60 along the slot 80, so two nails might be received by the cylinder at the same time, a projection 95 from the raceway-bar at the side from which the spring-wall approaches, extends into a circumferential slot 97 in said wall and in the cylinder. 65 This positively prevents such displacement. In the bores 22 in the arm-portions 23 of the base-casting, a nail-holding and nail-inverting roll 96 turns. Through this roll is a passage 98 for each of the cylinders 60. Each passage passes 70 through the roll and in its rotation may be alined

with the casing-opening 94 in a receiving position; with a casing-passage 99 leading to one of a set of nail-tubes 100 (Fig. 7) in a delivering position; and horizontally in registration with one of a set of testing passages 102 in the casing 5 (Figs. 6 and 8). As the nail-roll is driven, in a manner to be described, a cam 104 (Figs. 2 and 3) upon its end engages a projection 106 on the spindle 72, reciprocating this and causing the oscillation of the cylinders 60. The movements 10 of the roll and cylinders are so synchronized by this connection that as the nails are picked from the raceways by the spring-walls 82 and are dropped through the openings 94, they will be received by the roll-passages 98, which at that 15 time register with said openings.

To rotate the nail-roll 96, a lever 108 (Figs. 1 and 6) is fulcrumed beneath the trough 12 to turn about a horizontal spindle 110. This lever has two arms 112 and 113. The arm 112 carries at 20 its forward extremity a gear-segment 114 meshing with a pinion 116 fast upon the roll. A rod 118 joins this arm to a bell-crank-lever 120 which oscillated by a cam 122. During the operation of the apparatus, the periphery of the cam will engage a roll 123 upon the lever, but, initially, the roll is separated from the cam by means which will later be described. The operation of this cam may be as in the loader-controlling mechanism of Letters Patent of the United States No. 30 1,785,928, Benjamin, December 23, 1930, except that it is formed to serve the purposes of the present organization. A spring 124 holds the rod 118 normally down, to be elevated by the cam when a hand-lever 126, fulcrumed at 128 upon a 35 bracket projecting from the frame of the heeler F, is actuated by the operator against the force of a spring 129 (Fig. 3). The contour of the cam is such that the nail-roll may be turned from an initial testing position (Fig. 6), with its passages 40 98 in alinement with the casing-passages 102, to a delivering or advancing position in registration with the tubes 100 (Fig. 7), then reversely into receiving relation beneath the openings 94, and finally with a contained load of nails back into 45 alinement with the testing passages 102. Secured upon the end of the nail-roll is a feeler-controlling disk 130 (Figs. 2, 3 and 6 to 8), which has in its periphery a depression 132 to receive a roll 134 upon a lever 136 fulcrumed upon the forward 50 extremity of an outer trough-extension 14. At the opposite or inner extremity of the lever is a gear-segment 138, which acts on a pinion 140 fast upon a horizontal shaft 142 journaled beneath the trough-extentions. At one end of the 55 shaft is a collar 144, and this collar is joined to the adjacent trough-extension by a torsion-spring 146. The effect of this spring is to urge the shaft in a clockwise direction, as viewed from the right of the apparatus, and through the gearing 138, 60 149 force the roll 134 against the periphery of the disk 130 and thus cause said roll to enter the depression 132 when the latter registers with it. For each of the passages 98 in the nail-roll there is a pinion 148 on the shaft 142, this being connected to the shaft yieldably by a torsion-spring 150 (Fig. 10) joined to the pinion and to a collar 152 secured to the shaft. The rotation of the pinion upon the shaft under the influence of the spring is limited by a slot in a collar 154 fast on 70 the shaft, into which slot extends a projection 153 from the pinion. Each pinion meshes with a horizontally movable rack 154 upon a feeler-rod 156 mounted to reciprocate in the corresponding passage 102 (Fig. 6). Consequently, when the 75

roll 134 enters the depression 132, the feeler 156 is yieldably projected into the aligned nail-roll-passage 98 to test for the presence or absence of a nail. In so doing, it determines the position of a stop 160, which is movable by the corresponding pinion 148 in mesh with a rack 162 upon the stop. Each stop is guided by a stud 163 projecting from one of the arms 14 of the drum-casting for inclined downward and rearward movement between the corresponding collars 151 and 152, as may be seen in Figs. 1 and 10.

Projecting from the hub of the lever 108 is a lug 164 arranged for contact with a lug 166 upon the hub of a lever 168 (Figs. 6 and 7). Because of this relation, the levers 108 and 168 may either be turned separately or together. The lever 168 may be considered as a compound structure formed by projections from the spindle 110. In addition to the lug 166, there is a series of projections 170, one for each of the stops 160, and two arms 172 and 173 provided with respective gear-segments 174 and 175. The segment 174 meshes with a pinion 176 fixed upon a shaft 177 journaled transversely of the base 10. Also fast upon the shaft 177 is a pinion 179 engaged by a rack 178, movable horizontally by a link 180 connected to an arm 182 mounted to turn about a spindle 184. Also turning about the spindle is an arm 186, which is joined to a rod 188 connected to the treadle of the heeler F. When the rod is raised, as a consequence of the depression of the treadle and prior to the tripping of the heeler-clutch, a face 187 upon the arm 186 presses against a face 189 of the arm 182. This moves the rack 178 to the left (Fig. 6). The segment 175 of the lever-arm 173 meshes with a pinion 191 rotatable about a portion of the nail-roll 96 and has turning with it a disk 192 in close proximity to the disk 130 (Figs. 3 and 6). As best illustrated in Fig. 7, this disk 192 is provided at its periphery with a cam-wall 194 leading to a terminal-portion 195 which corresponds in depth to the depression 132. When the depressions 132 and 195 are in registration, it gives an opportunity for the roll 134 to enter them, so the lever 136 will be moved by the spring 146. This, through the gearing 138, 140, 148 and 154, will produce the testing action of the feelers 156. If these feelers, as they are moved into the passages 98 in the nail-roll 96, find all of these supplied with nails, such feeler-movement is arrested, as appears in Fig. 6, and the stops 160 are retained by their racks 162 above the ends of the projections 170 from the spindle 110, which projections form a portion of the lever 168. Therefore, said lever may be turned upon elevation of the treadle-rod 188, as already described. During rotation of the shaft 177 caused by this movement of the treadle-rod, it is turning a cam 200, which is fast upon it, carrying a circumferentially extended surface 203 upon said cam along a roll 202 upon the depending arm 113 of the lever 168. The contour of the cam 122 is such that at the beginning of a cycle, the spring 124 tends to cause the lever 108 to remove the nail-roll from the testing position which it should occupy. The cam 200, however, by engagement with the roll 202, initially retains the lever 108 against movement and the roll 123 spaced from the cam 122 (Fig. 6), with elements in the testing relation in spite of the influence of the spring. The pinion 179, in addition to rotating the cam 200 to produce the effect just stated, under the influence of the rack 178, is operated to shift the 75 rack in the opposite direction. This is effected

from the cam 122, by way of the lever 120, the rod 118, lever 108 and its projection 164, the projection 166 of lever 168, gearing 174, 176 and shaft 177. The arm-surface 189, from which the surface 187 became separated upon the retraction of the treadle-rod 188, is thus restored to its active position, the lost motion between the two surfaces being taken up. This movement occurs from the point at which the rack was left after the previous treadle-depression. 10

Considering now a complete operating cycle of this nail-supplying apparatus, there is at the termination of the preceding cycle a load of nails resting upon the drivers in the jack of the heeling machine F being supplied, ready for insertion, and there is another load in the passages 98 of the roll 96, their heads lying toward the rear. The loader-block L of the heeler is beneath the foot-plate P at which the nail-tubes 100 terminate, the loader-block-shutter 1 being closed. 15 The roll 96 is in the testing position, as appears in Fig. 6, the depression 132 of the roll-disk 130 and the depression 195 of the disk 192 are in registration, receiving the roll 134 of the lever 136; and the feelers 156 are within the roll-passages. 20 The plates 34 in the nail-receptacle 12, 26 are in continual rotation, their buckets 36 supplying nails N constantly to the raceway-slots, these nails hanging by their heads upon the bars 16 in unbroken series. Each series is held against 25 advance by the wall 81 of the slot 80 in the corresponding separating cylinder 60. The operator places a shoe upon the jack of the heeler, applies a heel to the heel-seat and depresses the treadle of the machine. As in Letters Patent of the 30 United States No. 1,855,405, MacKenzie, April 26, 1932, this brings down the pressure-abutments upon the heel to clamp the work upon the jack. The final effect of this treadle-action is to trip the heeler-clutch, so the drivers rise in the jack 40 and force the nails which they carry through the heel-seat-material into the heel. There is, however, an interval during which the rod 188, elevated by the treadle at this time, may act upon the distributor to cause the delivery to the 45 waiting loader-block of the nails contained in the roll-passages 98. First, however, the feelers 156 must be withdrawn to release the roll for its dumping movement. The rising treadle-rod forces the arm-surface 187 against the opposed surface 189 of the arm 182. This shifts the rack 178 to the left (Fig. 6), rotating the shaft 177 and turning the lever 168 anticlockwise to lower its segment 175. By this segment, the disk 192 is rotated clockwise to the position shown in Fig. 55 7, its depression 195 leaving the depression 132 of the disk 130, with which it is initially aligned, and its cam-surface 194 forcing the roll 134 of lever 136 out of the depression 132. The lever 136, acting through the intermediate gearing, 60 withdraws the feelers from the passages 98, leaving the roll free. This is on the assumption that the load of nails in the roll-passages was complete, and that the feelers have located the stops 160 above the ends of the projections 170 of the 65 lever 168, so the upward movement of the treadle-rod would not be interfered with. Had one or more of the feelers fully entered the passages 98, as appears in Fig. 8, the corresponding stops 160 would have been in the path of their projections 170, and the operator would have found the treadle locked against movement. Because of this, movement of the feeler-controlling disk 192 would be impossible, and the nail-roll would also be locked by the feelers. Looking at the 75

mechanism, he would observe from the positions of the stops which of the nail-roll-passages were empty. Horizontally aligned with each testing passage 102 in the casing surrounding the nail-roll is a passage 212, formed in a forward projection 213 from a frame-arm-portion 23. In this passage a loading rod 214 is guided. The rod is held normally against outward movement by a latch 216 pivoted on a collar 217 at the outer extremity of the rod, but may be released and retracted manually, freeing a slot 218 in the top of the projection 213 and opening into the passage 212. The slot is of the proper form to receive a nail with its head at the inner side. A nail having been introduced through the slot into each empty passage, the corresponding rod or rods 214 are forced in and latched. This carries the nail into the nail-roll-passage, the end of the rod furnishing a closure for the opening in the casing through which the introduction was made. A guard-bar 219, projecting from the collar 217 into the slot, maintains said slot normally closed and holds the collar and latch against rotation about the axis of the rod. The missing nails thus being supplied, the stops 160 will all be retracted. This unlocks the treadle-rod 188, which may be elevated in the actuation of the heeler F. The unlocking of the nail-roll by the withdrawal of the feelers results, preparing for the delivery of the load of nails from the roll.

During the withdrawal of the feelers following the successful depression of the treadle, the surface 203 of the cam 200 has been traveling along the roll 202 in a clockwise direction (Fig. 6) under the influence of the rack 178, the lever 168 being turned anticlockwise and the position of the lever 108 remaining unchanged. The lug 166, in the movement of the lever 168, has arrived in proximity to the lug 164 of the resting lever 108. Now, as the rack 178 approaches the end of the movement produced by the treadle-rod 188, the surface 203 of the cam 200 passes from and frees the roll 202 of lever 108. The spring 124 acts upon the lever 108, this being permitted by the initial spacing of the bell-crank-roll 123 from the cam 122, and the lever 108, with the companion lever 138 under the influence of the rack, assume the positions appearing in Fig. 7. The lever 108, through its segment 114, rotates the nail-roll clockwise to align the passages 98 with the casing-passages 99, so the load of nails passes, heads down, into the tubes 100 and falls therethrough upon the shutter 1 of the loader-block L. The control of the distributor by the treadle of the heeling machine is thus completed for the cycle, and the final treadle-depression causes the operation of the nailing mechanism to attach the heel to the jacked shoe by the previously delivered load of nails. Upon release of the treadle by the operator, the customary spring restores its rod 188 to the normal position, but, since the surface 187 of the arm 186 moves away from the surface 189 of the arm 182, the rack 178 and the elements directly governed by it are left in the relation shown in Fig. 7. Here, it will be seen that the lever-arms 112 and 173 have turned together in an anticlockwise direction, the nail-roll 98 and its disk 130 and the disk 192 rotating together clockwise, with the depressions 132 and 133 remaining in the spaced relation in which they were left after the withdrawal of the feelers 156 from the passages in the nail-roll.

The operator takes the heeled shoe from the jack and shifts the hand-lever 126. This is to

transfer to the jack the load of nails contained in the loader-block and to produce the movement of the nail-roll, first to the nail-receiving position and then to the testing position, where it controls the testing of the load. The clutch, gear and friction-drive mechanism C associated with the hand-lever, as in the Benjamin patent, actuates the loader-block. It also rotates the cam 122 through 360° in the direction of the arrow in Fig. 6. This raises the rod 118, causing the segment 114 of lever 108 to turn the nail-roll anticlockwise to a position in which its passages 98 register with the openings 94 of the casings 20. With the nail-roll, the separating cylinders 60 are receiving movement yieldably through the cam 104 and the connections which said cam actuates. At each cylinder, the spring-wall 82 enters between the nail which is in the open end of the slot 80 and the next nail, which is in the raceway-slot, and picks off the former, the end-wall of the slot at 92 transferring the separated nail to the casing-opening 94. The movements of the separating cylinders and the nail-roll are so synchronized by their actuating mechanism that, as each nail falls through an opening 94, it finds one of the passages 98 in the roll ready to receive it, and this it enters point down. Because of the engagement of the lug 164 with the lug 166, the lever 168 is turned with the lever 108. In this rotation, its segment 174 turns the shaft 177 and the cam 200 anticlockwise to bring the cam-surface 203 into the path which the roll 202 follows, when the lever 108 moves anticlockwise. At the same time, the pinion 179 restores the rack 178 to its normal position with the arm-surface 189 against the arm-surface 187. With the roll-passages 98 in their nail-receiving relation, the depression 195 of the disk 192 is in its initial position, while the depression 132 of the disk 130 has been carried beyond normal. The load of nails having been delivered to the roll, the contour of the rotating cam 122 allows the spring 124 to lower the rod 118 and, with it, the segment 114 of the lever 108, the lever 168 being left at rest, with the segment 175 in its position of maximum elevation. The nail-roll 98 is shifted clockwise by the segment 114 from the receiving position to the testing position of Fig. 6, the lever 108 being limited in its movement by the engagement of its roll 202 with the cam-surface 203. Simultaneously, the disk 130 is turned with the roll, so its depression 132 again comes into registration with the depression 195 in the now stationary disk 192. The roll 134 of the lever 136 is freed, so said lever is rotated anticlockwise by the spring 146, producing the testing action of the feelers 156 in the nail-roll-passages 98. Depending upon whether the load in the roll is complete or incomplete, the treadle-rod 188 of the heeler is either free for actuation or is locked by a stop or stops 160. In the latter case, the nail-roll is locked by the feelers in the passages. Actuation of the hand-lever 126 would merely cause the friction in the driving mechanism C to slip. The cycle is now terminated, and the elements are in the relation illustrated in Fig. 6.

There is further furnished an arrangement by which a double delivery of nails to the loader-block is additionally guarded against during a single operating cycle. This is illustrated in Figs. 2, 6 and 7. In considering this portion of the apparatus, it is to be noted that, at the beginning of a cycle, the lever 120 is held away from the cam 122 because of the retention of the 75

lever 108 by the cam 200. This position of the lever 120 is utilized to force a spring-pressed pin 222, which is carried by a rearward extension 224 from the lever 120 and guided in the frame-bracket, into a depression 226 in a surface 228 on the upper side of the hand-lever 126, adjacent to its fulcrum 128. This is as appears in Fig. 6, the hand-lever being found locked if the operator attempts to move it. Upon actuation of the treadle and the release of the lever 108 by the cam 200, the spring 124 turns the lever 120 anticlockwise until the roll 123 contacts with the cam 122. This lifts the pin 222 from the depression, unlocking the hand-lever. A heel having been nailed on a jacked shoe as a consequence of the operation of the treadle, and the completed work removed from the jack, the operator may shift the hand-lever to cause the delivery to the jack by the loader-block L of the nails which were received by the latter from the nail-roll 96 upon the treadle-depression. The hand-lever is held in its actuated position by a rotating surface 230, while the cam 122 turns through 360°, as in the previously mentioned Benjamin patent. The cam, acting upon the lever 120, again forces down the pin 222, but the movement of the hand-lever has carried away the depression 226, so said pin rides on the lever-surface 228 without interference with the movement of the lever. At the termination of the cycle, the lever 126 is released from the surface 230 and returned to its initial position by the spring 129, and when it arrives there, the pin enters the depression to again lock the lever. Therefore, the operator cannot shift the hand-lever to produce another nail-delivery or a nail-transfer until the preceding load has been driven out of the jack. In connection with the control of nail-delivery by the feelers 156, this locking of the lever has at least two advantages. The clutch of the mechanism C cannot be engaged, and therefore no harmful force can be applied to the feelers by movement of the nail-roll 96 under the power of the apparatus. Then, since the operator cannot move the hand-lever from its normal position, he is more promptly notified that there is a condition which must be corrected, and there is economy of effort.

Having described my invention, what I claim as new and desire to secure by Letters Patent of the United States is:

- 50 1. In a fastening-supplying apparatus, means for supplying fastenings, means by which groups of fastenings are separated, means for delivering the groups of fastenings to the machine to be supplied, and means acting between the separating means and the machine supplied for testing the groups of fastenings to determine their completeness.
- 55 2. In a fastening-supplying apparatus, means for supplying fastenings, a member by which the fastenings are temporarily held during their delivery to the machine to be supplied, testing means affected by the presence or absence of a fastening at the holding member, and means whereby the testing means controls the delivery of fastenings.
- 60 3. In a fastening-supplying apparatus, means for supplying fastenings, a member by which the fastenings are temporarily held during their delivery to the machine to be supplied, testing means affected by the presence or absence of a fastening at the holding member, and means whereby the testing means controls operation of the machine supplied with fastenings by the apparatus.
- 65 4. In a fastening-supplying apparatus, means for supplying fastenings, a member by which the fastenings are temporarily held during their delivery to the machine to be supplied, testing means affected by the presence or absence of a fastening at the holding member, and means whereby the absence of a fastening at the holding member prevents the use of the fastenings in the holding member.
- 70 5. In a fastening-supplying apparatus, means for supplying fastenings, means for advancing the supplied fastenings, a testing member arranged for contact with a fastening upon the advancing means, a member connected to the supplying apparatus and movable in the control of the machine to be supplied, and means governed by the testing member for locking such movable member against movement.
- 75 6. In a fastening-supplying apparatus, means for supplying fastenings, means for advancing the supplied fastenings, a testing member arranged for contact with a fastening upon the advancing means, a member movable to control the apparatus, and means governed by the testing member for locking such movable member against movement.
- 80 7. In a fastening-supplying apparatus, means for supplying fastenings, a holder having a passage receiving and delivering supplied fastenings, a testing member movable into and out of the passage, and means rendered active by movement of the testing member into the opening for preventing the use of the fastenings in the holder.
- 85 8. In a fastening-supplying apparatus, a race-way, a movable fastening-separator co-operating with the raceway, a movable fastening-holder to which the separator delivers, a feeler arranged to test the holder for fastenings, and means controlled by the feeler for preventing movement of the holder.
- 90 9. In a fastening-supplying apparatus, a race-way, a movable fastening-separator co-operating with the raceway, a movable fastening-holder to which the separator delivers, a feeler arranged to test the holder for fastenings, and means controlled by the feeler for preventing operation of the machine supplied with fastenings by the apparatus.
- 95 10. In a fastening-supplying apparatus, a race-way, a movable fastening-separator co-operating with the raceway, a movable fastening-holder to which the separator delivers, means for moving the holder, means for communicating movement of the holder to the separator, a feeler arranged to test the holder for fastenings, and means controlled by the feeler for preventing movement of the holder.
- 100 11. In a fastening-supplying apparatus, a plurality of raceways, an oscillatory separator co-operating with each raceway and engaging successive fastenings to withdraw them from the raceway, an oscillatory fastening-roll provided with passages corresponding to the separators, means for oscillating the fastening-roll, and means for communicating the oscillation of the fastening-roll to the separators.
- 105 12. In a fastening-supplying apparatus, a plurality of raceways, an oscillatory separator co-operating with each raceway, an oscillatory fastening-roll provided with passages corresponding to the separators, means for oscillating the fastening-roll, and yieldable means for communicating the oscillation of the fastening-roll to each separator.
- 110 13. In a fastening-supplying apparatus, a plu-

rality of raceways, an oscillatory separator co-operating with each raceway, an oscillatory fastening-roll provided with passages corresponding to the separators, means for oscillating the fastening-roll, means for communicating the oscillation of the fastening-roll to the separators, a feeler movable into and out of each roll-passage, and means controlled by the feelers for preventing the delivery of fastenings from the fastening roll.

14. In a nail-supplying apparatus, a casing provided with a supply-opening, a delivery-opening and a testing-opening, a roll movable in the casing and provided with a nail-holding passage, means for turning the roll to bring the passage into successive registration with the three openings, a feeler movable through the testing-opening into the roll-passage, and means controlled by the feeler for preventing movement of the roll.

15. In a nail-supplying apparatus, a casing provided with a supply-opening, a delivery-opening and a testing-opening, a roll movable in the casing and provided with a nail-holding passage initially in registration with the testing-opening, a feeler extending from the testing-opening into the roll-passage, and means for withdrawing the feeler from the passage.

16. In a nail-supplying apparatus, a casing provided with a supply-opening, a delivery-opening and a testing-opening, a roll movable in the casing and provided with a nail-holding passage initially in registration with the testing-opening, a feeler extending from the testing-opening into the roll-passage, means for withdrawing the feeler from the passage, and means depending upon the position of the feeler in the passage for preventing the withdrawal of said feeler.

17. In a fastening-supplying apparatus, a casing provided with a fastening-delivering opening, a fastening-receiving opening and a testing-opening, and a fastening-holder movable in the casing and having a passage which may register with any one of the openings.

18. In a fastening-supplying apparatus, a casing provided with a fastening-delivering opening, a fastening-receiving opening and a testing-opening, and a fastening-holder movable in the casing and having a passage which may register with any one of the openings, the holder inverting the fastening between the receiving and delivering openings.

19. In a fastening-supplying apparatus, a casing, a roll rotatable in the casing and provided with a passage, means for testing the passage to determine the presence or absence of a fastening, and means for turning the roll after testing to invert a fastening in the passage.

20. In a fastening-supplying apparatus, a casing provided with a fastening-delivering opening, a fastening-receiving opening and a testing-opening, a fastening-holder movable in the casing and having a passage which may register with any one of the openings, and a fastening-separator delivering to the holder-passage through the receiving-opening.

21. In a fastening-supplying apparatus, a casing provided with a fastening-delivering opening, a fastening-receiving opening and a testing-opening, a fastening-holder movable in the casing and having a passage which may register with any one of the openings, a fastening-testing member movable through the testing-opening into the holder-passage, and means controlled by

the testing member for preventing movement of the holder.

22. In a nail-supplying apparatus, a casing provided with a nail-delivering opening, a nail-receiving opening and a testing-opening, a nail-roll rotatable in the casing and having a passage which may register with any one of the casing-openings, a nail-separating cylinder delivering to the roll-passage through the receiving-opening, a feeler movable through the testing-opening into the roll-passage, and means controlled by the feeler for preventing movement of the roll.

23. In a fastening-supplying apparatus, a roll having a fastening-holding passage and being rotatable into delivering, receiving and testing positions, a rotatable device for controlling the rotation of the roll to its receiving and testing positions, and means other than such device for turning the roll to its delivering position.

24. In a fastening-supplying apparatus, a roll having a fastening-holding passage and being rotatable into delivering, receiving and testing positions, a rotatable cam by which the roll is rotated in one direction to certain of its positions, and means for rotating the roll in the opposite direction to another of its positions.

25. In a fastening-supplying apparatus, a roll having a fastening-holding passage and being rotatable into delivering, receiving and testing positions, a rotatable cam by which the roll is rotated to certain of its positions, a member movable by the operator to control the rotation of the cam, means for rotating the roll to another of its positions, and a member movable in the control of the machine supplied with fastenings by the apparatus to govern the last-mentioned means.

26. In a fastening-supplying apparatus, a roll having a fastening-holding passage and being rotatable into different positions, a lever geared to the roll, means for oscillating the lever, and means arranged to render the oscillating means ineffective during a portion of an operating cycle.

27. In a fastening-supplying apparatus, a roll having a fastening-holding passage and being rotatable into different positions, a lever geared to the roll, a rotatable cam by which the lever is oscillated, and a rotatable cam by which the lever is held against movement.

28. In a fastening-supplying apparatus, a roll having a fastening-holding passage and being rotatable into different positions, a lever geared to the roll, a rotatable cam by which the lever is oscillated, a hand-lever by which said cam is controlled, a rotatable cam by which the lever is held against movement, and a rod movable in the control of the machine supplied with fastenings by the apparatus and governing the last-mentioned cam.

29. In a fastening-supplying apparatus, a member having fastening-holding means and being movable to different positions, a movable testing member with which the fastening-holding means co-operates in one of its positions, and means movable with the holding member to control the testing movement of the testing member.

30. In a fastening-supplying apparatus, a member having fastening-holding means and being movable to different positions, a movable testing member with which the fastening-holding means co-operates in one of its positions, means movable with the holding member to control the testing movement of the testing member, and

- means movable by the operator to control such testing movement.
31. In a fastening-supplying apparatus, a roll having a fastening-holding passage and being rotatable to different positions, a movable testing member with which the passage is alined in one of its positions, and means rotatable with the roll to control the movement of the testing member into and out of the passage.
32. In a fastening-supplying apparatus, a roll having a fastening-holding passage and being rotatable to different positions, a movable testing member with which the passage is alined in one of its positions, means rotatable with the roll to control the movement of the testing member, and means movable by the operator to control the movement of the testing member.
33. In a fastening-supplying apparatus, a roll having a depression and a fastening-holding passage and being rotatable to different positions, a disk rotatable in proximity to the roll and having a depression which may register with the roll-depression, means for moving the roll and disk relatively to bring the depressions into and out of registration, and a testing member arranged to enter the roll-passage and controlled by the relation of the depressions.
34. In a fastening-supplying apparatus, a roll having a depression and a fastening-holding passage and being rotatable to different positions, a disk rotatable in proximity to the roll and having a depression which may register with the roll-depression, means for moving the roll and disk relatively to bring the depressions into and out of registration, and a testing member arranged to enter the roll-passage when the depressions are in registration.
35. In a fastening-supplying apparatus, a rotatable roll having a depression and a fastening-holding passage and being rotatable to different positions, a disk rotatable in proximity to the roll and having a depression which may register with the roll-depression, means for moving the roll and disk relatively to bring the depressions into and out of registration, a testing member arranged to enter the roll-passage when the depressions are in registration, and means associated with one of the depressions for removing the testing member from the passage.
36. In a fastening-supplying apparatus, a rotatable roll having a depression and a fastening-holding passage and being rotatable to different positions, a disk rotatable in proximity to the roll and having a depression which may register with the roll-depression, means for moving the roll and disk relatively to bring the depressions into and out of registration, and a testing member arranged to enter the roll-passage and controlled by the relation of the depressions, there being a cam-incine upon the periphery of the disk leading from its depression to remove the testing member from the passage.
37. In a nail-supplying apparatus, a rotatable roll provided with a nail-holding passage, a disk secured to the roll and having a peripheral depression, a disk rotatable upon the roll and having a depression which may register with the roll-depression, a lever one extremity of which rests upon the peripheries of the disks to enter the depressions when they are in registration, a feeler movable into and out of the roll-passage, and gearing connecting the lever and feeler.
38. In a nail-supplying apparatus, a rotatable roll provided with a nail-holding passage, a disk secured to the roll and having a peripheral de-
- pression, a disk rotatable upon the roll and having a depression which may register with the roll-depression, a lever one extremity of which rests upon the peripheries of the disks to enter the depressions when they are in registration, a feeler movable into and out of the roll-passage, gearing connecting the lever and feeler, and a spring acting upon the lever to force it into engagement with the peripheries of the disks.
39. In a nail-supplying apparatus, a rotatable roll provided with a nail-holding passage, a disk secured to the roll and having a peripheral depression, a disk rotatable upon the roll and having a depression which may register with the roll-depression, a lever one extremity of which rests upon the peripheries of the disks to enter the depressions when they are in registration, a feeler movable into and out of the roll-passage, gearing actuated by the lever, and yieldable means for connecting the gearing to the feeler.
40. In a fastening-supplying apparatus, a movable holder provided with plural fastening-holding means, a movable testing member individual to each holding means, actuating means common to the plural testing members, and yieldable means for connecting each testing member to the actuating means.
41. In a fastening-supplying apparatus, a rotatable roll provided with a plurality of fastening-receiving passages, a feeler movable into and out of each passage, actuating means common to the plural feelers, and yieldable means for connecting each feeler to the actuating means.
42. In a fastening-supplying apparatus, a rotatable roll provided with a plurality of fastening-receiving passages, a feeler movable into and out of each passage, a rotatable shaft, gearing for each feeler, and a spring connecting the gearing of each feeler to the shaft.
43. In a fastening-supplying apparatus, a rotatable roll provided with a plurality of fastening-receiving passages, a feeler movable into and out of each passage, controlling means, a shaft rotatable in proximity to the roll, a lever fixed to the shaft and being under the influence of the controlling means, a pinion individual to each feeler and free to turn about the shaft, a spring joining each pinion to the shaft, and a rack connected to the feeler and with which the pinion meshes.
44. In a fastening-supplying apparatus, a rotatable roll having a fastening-holding passage rotatable to different positions, a movable testing member with which the passage is alined in one of its positions, means for moving the testing member into and out of the passage, and a member movable with the testing member and arranged to prevent the operation of the machine to be supplied with fastenings by the apparatus.
45. In a fastening-supplying apparatus, a rotatable roll having a fastening-holding passage rotatable to different positions, a movable testing member with which the passage is alined in one of its positions, means for moving the testing member into and out of the passage, and a stop member movable by said moving means.
46. In a fastening-supplying apparatus, a rotatable roll having a fastening-holding passage rotatable to different positions and being provided with a depression, a disk rotatable in proximity to the roll and having a depression which may register with the roll-depression, means for moving the roll and disk relatively to bring the depressions into and out of registration, a testing member arranged to enter the roll-passage and controlled by the relation of the depressions, and

a stop member controlled by the position of the testing member.

47. In a fastening-supplying apparatus, a rotatable roll having a fastening-holding passage 5 rotatable to different positions and being provided with a depression, a disk rotatable in proximity to the roll and having a depression which may register with the roll-depression, means for moving the roll and disk relatively to bring the depressions into and out of registration, a testing member arranged to enter the roll-passage and controlled by the relation of the depressions, and a stop movable with the testing member to limit the relative movement between the roll and disk.

48. In a nail-supplying apparatus, a rotatable roll provided with a nail-holding passage, a disk secured to the roll and having a peripheral depression, a disk rotatable upon the roll and having a depression which may register with the roll-depression, a lever one extremity of which rests upon the peripheries of the disks to enter the depressions when they are in registration, a feeler movable into and out of the roll-passage, gearing connecting the lever and feeler, and a stop movable by said gearing to prevent rotation of the disk upon the roll.

49. In a fastening-supplying apparatus, a rotatable roll provided with a fastening-holding passage movable into delivering, receiving and 30 testing positions, a testing member movable into and out of the passage, a rotatable member controlling the movement of the testing member, a member movable by the operator to cause the rotation of the roll, and a member for actuation by the operator to rotate the controlling member.

50. In a fastening-supplying apparatus, a rotatable roll provided with a fastening-holding passage movable into delivering, receiving and testing positions, a testing member movable into and 40 out of the passage, a rotatable member controlling the movement of the testing member, a member movable by the operator to cause the rotation of the roll, and a member for actuation by the operator to rotate the controlling member, the operator-actuated member also governing the rotation of the roll.

51. In a fastening-supplying apparatus, a rotatable roll provided with a fastening-holding passage movable into delivering, receiving and 50 testing positions, a primary lever for rotating the roll, a testing member movable into and out of the passage, a rotatable member controlling the movement of the testing member, a secondary lever for rotating the controlling member, means governed by the operator for moving the primary lever, and means governed by the operator for moving the secondary lever.

52. In a fastening-supplying apparatus, a rotatable roll provided with a fastening-holding passage movable into delivering, receiving and 60 testing positions, a lever movable to rotate the roll, a testing member movable into and out of the passage, a rotatable member controlling the movement of the testing member, a lever movable to rotate the controlling member, and means carried by one of the levers for moving the other.

53. In a fastening-supplying apparatus, a rotatable roll provided with a fastening-holding passage movable into delivering, receiving and 70 testing positions, a primary lever for rotating the roll, a testing member movable into and out of the passage, a rotatable member controlling the movement of the testing member, a secondary lever for rotating the controlling member, means governed by the operator for moving the primary

lever, and means governed by the operator for moving the secondary lever, the primary lever engaging the secondary lever to effect its rotation.

54. In a fastening-supplying apparatus, a rotatable roll provided with a fastening-holding passage movable into delivering, receiving and 5 testing positions, a primary lever for rotating the roll, a testing member movable into and out of the passage, a stop positioned by the testing member, a rotatable member controlling the movement of the testing member, a secondary lever for rotating the controlling member, the secondary lever having an arm for engagement with the stop, means governed by the operator for moving the primary lever, and means governed 10 by the operator for moving the secondary lever.

55. In a nail-supplying apparatus, a rotatable roll provided with a nail-holding passage, means for rotating the roll to delivering, receiving and 15 testing positions, a feeler movable into and out of the roll-passage, a stop movable with the feeler, a rotatable controlling member for the feeler, and a lever by which the controlling member is rotated, said lever having an arm for engagement with the stop.

56. In a nail-supplying apparatus, a rotatable roll provided with nail-holding passages, means for rotating the roll to delivering, receiving and testing positions, feelers movable into and out of the roll-passages, a stop movable with each feeler, a rotatable controlling member for the feelers, and a lever by which the controlling member is rotated, said lever having arms for engagement 20 with the stops.

57. In a nail-supplying apparatus, a rotatable roll provided with nail-holding passages, means for rotating the roll to delivering, receiving and testing positions, feelers movable into and out of the roll-passages, a stop movable with each feeler, a rotatable controlling member for the feelers, and a lever having an arm through which it is 25 oscillated, an arm by which the controlling member is rotated and arms for engagement with the stops.

58. In a nail-supplying apparatus, a rotatable roll provided with a nail-holding passage, means for rotating the roll to delivering, receiving and testing positions, a feeler movable into and out of the roll-passage, a stop movable with the feeler, a rotatable controlling member for the feeler, a lever by which the controlling member is rotated, said lever having an arm for engagement with the stop, and a member movable in the control of the machine supplied with nails by the apparatus and connected to the lever to oscillate it.

59. In a nail-supplying apparatus, a rotatable roll provided with nail-holding passages, means for rotating the roll to delivering, receiving and testing positions, feelers movable into and out of the roll-passages, a stop movable with each feeler, a rotatable controlling member for the feelers, a lever having an arm through which it is oscillated, an arm by which the controlling member is rotated and arms for engagement with the stops, and actuating connections to the first-mentioned lever-arm, in which connections there is provision for lost motion.

60. In a nail-supplying apparatus, a rotatable roll provided with nail-holding passages, means for rotating the roll to delivering, receiving and testing positions, feelers movable into and out of the roll-passages, a stop movable with each feeler, a rotatable controlling member for the feelers, a lever having an arm through which 70

- it is oscillated, an arm by which the controlling member is rotated and arms for engagement with the stops, actuating connections to the first-mentioned lever-arm, in which connections there is provision for lost motion, and means for moving the lever to take up the lost motion.
- 5 61. In a nail-supplying apparatus, a rotatable roll provided with nail-holding passages, means for rotating the roll to delivering, receiving and testing positions, feelers movable into and out of the roll-passages, a stop movable with each feeler, a rotatable controlling member for the feelers, a lever having an arm through which it is oscillated, an arm by which the controlling member is rotated and arms for engagement with the stops, a rack geared to the first-mentioned arm, and a rod movable in the control of the machine supplied with nails by the apparatus and arranged to move the rack.
- 10 62. In a nail-supplying apparatus, a rotatable roll provided with nail-holding passages, means for rotating the roll to delivering, receiving and testing positions, feelers movable into and out of the roll-passages, a stop movable with each feeler, a rotatable controlling member for the feelers, a lever having an arm through which it is oscillated, an arm by which the controlling member is rotated and arms for engagement with the stops, a rack geared to the first-mentioned arm, a rod movable in the control of the machine supplied with nails by the apparatus and arranged to move the rack in one direction, and means for moving the lever to move the rack in the opposite direction.
- 15 63. In a nail-supplying apparatus, a rotatable roll provided with a nail-holding passage, a lever for rotating the nail-roll, a feeler movable into and out of the roll-passage, a stop movable with the feeler, a rotatable controlling member for the feeler, a lever by which the controlling member is rotated, a shaft geared to the lever of the controlling member, means for rotating the shaft, and a cam carried by the shaft and acting upon the nail-roll-lever.
- 20 64. In a nail-supplying apparatus, a rotatable roll provided with a nail-holding passage, a lever for rotating the nail-roll, a feeler movable into and out of the roll-passage, a stop movable with the feeler, a rotatable controlling member for the feeler, a lever by which the controlling member is rotated, a shaft geared to the lever of the controlling member, an actuating member movable in the control of the machine supplied with nails by the apparatus for rotating the shaft, and a cam carried by the shaft and acting upon the nail-roll-lever.
- 25 65. In a nail-supplying apparatus, a rotatable roll provided with a nail-holding passage, a lever for rotating the nail-roll to delivering, receiving and testing positions, a feeler movable into and out of the roll-passage, a stop movable with the feeler, a rotatable controlling member for the feeler, a lever by which the controlling member is rotated, a shaft geared to the lever of the controlling member, an actuating member movable in the control of the machine supplied with nails by the apparatus for rotating the shaft, a cam carried by the shaft for holding the nail-roll-lever to determine the testing position of the nail-roll and for releasing said lever for movement of the roll to delivering position, and means for moving the nail-roll-lever to turn the roll to receiving position and simultaneously 30 moving the lever of the controlling member and

thereby restoring the actuating member to its initial position.

66. In a fastening-supplying apparatus, a fastening-holder, automatic means for supplying fastenings to the holder, and a member movable by the operator to introduce into the holder fastenings missed by the automatic means.

67. In a fastening-supplying apparatus, a fastening-holder provided with a plurality of passages to receive the fastenings of a complete load, 10 automatic means for supplying fastenings to all the passages, and a member movable by the operator to insert in each passage a fastening which may have been missed by the automatic means.

68. In a nail-supplying apparatus, an oscillatory nail-roll provided with a passage extending through it, means movable into one end of the passage for testing nails therein, and means for introducing nails into the opposite end of the 20 passage.

69. In a nail-supplying apparatus, an oscillatory nail-roll provided with a passage extending through it and movable into nail-delivering, nail-receiving and nail-testing positions, means for 25 introducing nails into the passage in the receiving position, and means arranged to introduce nails into the passage in the testing position.

70. In a nail-supplying apparatus, an oscillatory nail-roll provided with a passage extending 30 through it and movable into nail-delivering, nail-receiving and nail-testing positions, means for introducing nails into the passage in the receiving position, a feeler movable into the passage in the testing position, and a loading member movable to introduce a nail into the passage 35 in the testing position.

71. In a nail-supplying apparatus, a casing provided with opposite openings, a nail-roll rotatable in the casing and having a passage which 40 may be brought into registration with the openings, a feeler movable in one opening in co-operation with the passage, and a nail-loading member movable in co-operation with the passage in the other opening.

72. In a nail-supplying apparatus, a casing provided with opposite openings, a nail-roll rotatable in the casing and having a passage which may be brought into registration with the openings, a yieldable feeler movable in one opening 50 in co-operation with the passage, a nail-loading member movable toward the passage in the other opening, and means for retaining the loading member in its advanced position.

73. In a nail-supplying apparatus, a casing 55 provided with openings, a nail-roll rotatable in the casing and having a passage for registration with the openings, and a nail-loading rod arranged to reciprocate in one of the casing-openings.

74. In a nail-supplying apparatus, a casing provided with openings, a nail-roll rotatable in the casing and having a passage for registration with the openings, a nail-loading rod arranged to reciprocate in one of the casing-openings, and 60 a latch arranged to retain the rod with its nail-engaging end in proximity to the nail-roll.

75. In a nail-supplying apparatus, a casing provided with an extension and with openings, the extension having a passage alined with one of 70 the openings and a nail-receiving slot through the extension into the passage, a nail-roll rotatable in the casing and having a passage for registration with the openings, and a member movable in the extension-passage and arranged to 75

introduce into the roll-passage a nail supplied through the slot in the extension.

76. In a nail-supplying apparatus, a casing provided with an extension and with openings, the extension having a passage alined with one of the openings and a nail-receiving slot through the extension into the passage, a nail-roll rotatable in the casing and having a passage for registration with the openings, a member movable in the extension-passage and arranged to introduce into the roll-passage a nail supplied through the slot in the extension, and means movable with the member for closing the slot.

77. In a nail-supplying apparatus, a casing provided with an extension and with openings, the extension having a passage alined with one of the openings and a nail-receiving slot through the extension into the passage, a nail-roll rotatable in the casing and having a passage for registration with the openings, a rod movable in the extension-passage and arranged to introduce into the roll-passage a nail supplied through the slot, a collar on the outer end of the rod, and a latch carried by the collar for engagement with the extension.

78. In a nail-supplying apparatus, a casing provided with an extension and with openings, the extension having a passage alined with one of the openings and a nail-receiving slot through the extension into the passage, a nail-roll rotatable in the casing and having a passage for registration with the openings, a rod movable in the extension-passage and arranged to introduce into the roll-passage a nail supplied through the slot, a collar on the outer end of the rod, and a guard extending from the collar and movable in the slot.

79. In a fastening-supplying apparatus, a movable fastening-delivering member, an operator-actuated member by which the movement of the fastening-delivering member is controlled, and means for locking the controlling member against movement by the operator.

80. In a fastening-supplying apparatus, a movable delivering member arranged to hold a load of fastenings at the beginning of an operating cycle, an operator-actuated member by which the movement of the fastening-delivering member is controlled, means for locking the operator-actuated member against movement, a second operator-actuated member by which the movement of the fastening-delivering member is controlled, and means for releasing the locking means as a result of the movement of the second operator-actuated member.

81. In a fastening-supplying apparatus, a movable delivering member arranged to hold a load of fastenings at the beginning of an operating cycle, an operator-actuated member by which the movement of the fastening-delivering member is controlled, means for locking the operator-actuated member against movement, a member movable in the control of the machine to be supplied with fastenings by the apparatus, and means for releasing the locking means as a result of the movement of the last-mentioned member.

82. In a nail-supplying apparatus, a rotatable nail-roll, a movable operating member for the roll, connections for transmitting the movement of the operating member to the roll, an operator-actuated member by which the movement of the operating member is governed, and a lock for the operator-actuated member, the lock being con-

trolled by the relation between the operating member and the transmitting connections.

83. In a nail-supplying apparatus, a rotatable nail-roll, a movable operating member for the roll, connections for transmitting the movement of the operating member to the roll, an operator-actuated member by which the movement of the operating member is governed, a lock for the operator-actuated member, the lock being controlled by the relation between the operating member and the transmitting connections, and a second operator-actuated member for varying such relation.

84. In a nail-supplying apparatus, a rotatable nail-roll, a rotatable cam, a hand-lever for controlling the rotation of the cam, a lever connected to the roll and movable by the cam but held initially out of engagement therewith, a hand-lever, a lock for the hand-lever controlled by the cam-lever, and means for releasing the cam-lever for engagement with the cam and the removal of the lock from the hand-lever.

85. In a nail-supplying apparatus, a rotatable nail-roll, a rotatable cam, a hand-lever for controlling the rotation of the cam, a lever connected to the roll and movable by the cam but held initially out of engagement therewith, a hand-lever, a lock for the hand-lever controlled by the cam-lever, and means made active in the control of the machine to be supplied with nails by the apparatus for releasing the cam-lever for engagement with the cam and the removal of the lock from the hand-lever.

86. In combination, a fastening-distributor provided with means for testing each load of fastenings which it is to deliver and for preventing delivery if the load is incomplete, a movable device for transferring each load of fastenings from the distributor, and means for preventing movement of the device until the preceding load transferred has been used by the machine supplied.

87. In a fastening-distributor, a stationary receptacle, a rotatable shaft extending through the receptacle, disks fixed to the shaft and dividing the receptacle into separate fastening-compartments, fastening-elevating buckets carried by the disks, and raceways mounted upon the receptacle and to which the buckets deliver.

88. In a fastening-distributor, a stationary receptacle, a rotatable shaft extending through the receptacle, disks fixed to the shaft and dividing the receptacle into separate fastening-compartments, series of fastening-elevating buckets carried upon opposite sides of the disks, the opposite series upon a disk being in staggered relation, and raceways mounted upon the receptacle and to which the buckets deliver.

89. In a fastening-distributor, a stationary receptacle, a rotatable shaft extending through the receptacle, disks fixed to the shaft and dividing the receptacle into separate fastening-compartments, a door individual to each compartment pivoted upon the receptacle, fastening-elevating buckets carried by the disks, and raceways mounted upon the receptacle and to which the buckets deliver.

90. In a fastening-distributor, a stationary receptacle, a rotatable shaft extending through the receptacle, disks fixed to the shaft and dividing the receptacle into separate fastening-compartments, fastening-elevating buckets carried by the disks within the receptacle, the terminal disks furnishing closures for the ends of the recep-

tacle, and raceways mounted upon the receptacle and to which the buckets deliver.

91. In a fastening-distributor, a trough provided with downwardly and outwardly inclined 5 projections, pairs of raceway-bars spaced from each other upon the projections and extending into the trough, a cover hinged upon the trough and furnishing a closure therefor, said cover having a portion covering the raceway outside the 10 trough, and means for delivering fastenings from the trough to the raceway.

92. In a fastening-distributor, a trough provided with downwardly and outwardly inclined 15 projections, pairs of raceway-bars spaced from each other upon the projections and extending into the trough, a cover hinged upon the trough and having a portion covering the raceway outside the trough, a rotatable shaft extending through the trough, disks fixed to the shaft, and 20 brackets carried by the disks and delivering to the raceways.

93. In a fastening-distributor, a trough, a raceway leading therefrom, means rotatable in the trough and delivering fastenings to the raceway, 25 a cover mounted upon the trough, movable clearing means carried by the cover and co-operating with the raceway, and means for transmitting the movement of the delivering means to the clearing means.

94. In a fastening-distributor, a trough, a raceway leading therefrom, buckets revoluble in the trough and delivering to the raceway, gearing by which the buckets are revolved, a cover mounted upon the trough, and clearing means 30 for the raceway rotatable upon the cover and actuated by the bucket-gearing.

95. In a fastening-distributor, a trough, a plurality of raceways leading therefrom, a shaft extending through the trough, buckets revoluble by the shaft, a gear fixed to the shaft and by which 40 it is rotated, a cover for the trough, a shaft journaled in and extending longitudinally of the cover, a clearing-wheel for each raceway secured to the cover-shaft, and a pinion fast upon the cover-shaft and driven from the trough-shaft.

96. In a fastening-distributor, a stationary receptacle provided with a downward and outward projection furnishing a raceway, the lower end 45 of the projection having a casing with a bottom-wall in which is an opening, and a separating cylinder arranged to move in the casing to exert a force upon a fastening to withdraw it from the raceway and thereafter to a position in which the withdrawn fastening is delivered by gravity through the casing-opening.

97. In a fastening-distributor, a stationary receptacle provided with a downward and outward projection furnishing a raceway, the lower end 50 of the projection having a casing, a separator arranged to move in the casing between a position in which a fastening is received from the raceway and a position in which the received fastening is delivered from the casing, a cover hinged upon the receptacle and having an extension over the raceway outside the trough, and a cover for the casing hinged upon the extension.

98. In a fastening-distributor, a raceway, and a member movable at the delivery-end of the raceway and having a flexible projection arranged to engage the terminal fastening and separate it 55 from the raceway.

99. In a fastening-distributor, a raceway, a member movable at the delivery-end of the race-

way, and a spring-wall secured to the member and arranged to engage the terminal fastening to separate it from the raceway.

100. In a fastening-distributor, a raceway, a member movable at the delivery-end of the raceway, and a spring-wall secured to the member and arranged to engage the terminal fastening to separate it from the raceway, the fastening-engaging end of the wall being inclined downwardly and rearwardly with respect to the direction of 10 separating movement of the wall.

101. In a fastening-distributor, a raceway, a cylinder mounted to oscillate at the delivery-end of the raceway, there being a fastening-receiving recess in the wall of the cylinder, and a flexible 15 fastening-separating wall secured to the cylinder outside the recess.

102. In a nail-distributor, a raceway along which nails are advanced in a series hanging by their heads, a casing at the delivery-end of the 20 raceway, there being an opening at the bottom of the casing of a size sufficient to pass the head of a nail, and a cylinder rotatable in the casing and having a recess in its wall and a nail-engaging wall extending outside the recess to furnish 25 a receiving slot, the slot at the end opposite the nail-engaging end of the wall being of a size sufficient to pass the head of a nail and movable by the cylinder to register with the casing-opening.

103. In a nail-distributor, a raceway along 30 which nails are advanced in a series hanging by their heads, a casing at the delivery-end of the raceway, there being an opening at the bottom of the casing of a size sufficient to pass the head of a nail, and a cylinder rotatable in the casing and 35 having a recess in its wall and a flexible wall secured to the cylinder outside the recess and furnishing a slot, there being an opening at the end of the wall into the recess and an enlargement at the opposite extremity of the recess of a sufficient 40 size to pass the head of a nail.

104. In a fastening-distributor, a series of fastening-raceways, a movable fastening-separator co-operating with each raceway, an actuating member common to plural separators, and a 45 spring interposed between each separator and the actuating member.

105. In a fastening-distributor, a series of fastening-raceways, a rotatable fastening-separator 50 co-operating with each raceway and being provided with teeth, a toothed member meshing with the teeth of each separator and being individual thereto, and a reciprocating actuating member common to the toothed members.

106. In a fastening-distributor, a series of fastening-raceways, a rotatable fastening-separator 55 co-operating with each raceway and being provided with teeth, a toothed member meshing with the teeth of each separator and being individual thereto, a reciprocating actuating member common to the toothed members, and a spring associated with each toothed member and transmitting thereto the movement of the actuating member.

107. In a fastening-distributor, a series of fastening-raceways, a rotatable fastening-separator 60 co-operating with each raceway and being provided with teeth, a rack-block meshing with the teeth of each separator, a rod passing through the blocks and provided with a recess corresponding to each block, and a spring seated in each recess and acting upon the associated block.

JOHN T. LANCASTER.
